2 SHEETS—SHEET 2.

UNITED STATES PATENT OFFICE.

ROBERT W. VAN BUREN, OF WHITE PLAINS, NEW YORK.

GARMENT-PRESSING DEVICE.

1,275,801.

Specification of Letters Patent. Patented Aug. 13, 1918.

Application filed October 11, 1917. Serial No. 195,944.

To all whom it may concern:

Be it known that I, ROBERT W. VAN BUREN, a citizen of the United States, residing at Independence street, White Plains, 5 in the county of Westchester and State of New York, have invented certain new and useful Improvements in Garment-Pressing Devices, of which the following is a specification.

10 This invention relates to apparel apparatus and has more especial reference to a garment pressing device.

The invention has for its principal object to provide a device for receiving trousers 15 and pressing the same in order that they will be properly shaped in a manner to prevent injury to the fabric.

Another object of the invention is to provide a device of the character mentioned 20 having novel clamping means, the same serving to prevent wrinkling of the trousers during the pressing thereof and insuring proper stretching of the same during the pressing operation.

25 It is also an object of the invention to provide a garment pressing device that may be folded into compact form when not in use and placed in a limited or confined space.

The foregoing together with additional 30 advantageous details and arrangement of parts of the preferred embodiment of my invention will be clear from the specific description hereinafter contained, when read in connection with the accompanying drawings forming part thereof, wherein said embodiment of the invention is illustrated for the purpose of imparting a full understanding 35 of the present improvements.

In the drawings:—

40 Figure 1 is a plan view of the device when in open position;

Fig. 2 is a similar view of the same when in closed position;

Fig. 3 is a vertical transverse section 45 therethrough;

Fig. 4 is a fragmentary detail in section showing the connection between the pressing leaves and the body portion of the device;

50 Fig. 5 is a similar section;

Fig. 6 is a fragmentary detail in perspective of one of the keepers or ears formed on the body portion of the device;

Fig. 7 is a fragmentary side elevation of 55 the device; and

Fig. 8 is a disassembled detail in perspective of the garment stretching means and the bearings for one end of the same.

Similar characters of reference refer to similar parts throughout the several views 60 of the drawings.

Having more particular reference to the drawings, 1 represents the body portion of the device, the same being tapered and formed in sections, which sections are 65

hingedly connected as indicated by the numeral 2. A series of ears 3 are formed upon the beveled marginal edge of the sectional body portion, and are rolled upon themselves to provide hinged leaves whereby pressing 70

boards or leaves 4 having similar ears 5 formed upon the adjacent marginal edges thereof can be hingedly connected to the sectional body portion 1, it of course being understood that bearing pins are passed 75

through the alined leaves or ears formed on the leaves 4 and the sections of the body 1. Rolled flanges 6 are formed upon the inclined marginal edges of the sections of the body portion 1 and in order that the leaves 80

4 may be swung past the same, recessed portions 7 are formed therein. Other rolled flanges or ears 8 are formed upon the opposite marginal edges of the sections of the body portion 1 and as will be noted, some 85

of the same are wider than others, the purpose of which will be subsequently apparent. Seats or notches 9 are formed in the marginal edges of certain of the rolled flanges 8 and serve as means for permitting positive 90

connection with turn buttons 10 pivotally mounted upon the pressing leaves 4 adjacent the free extremities thereof.

Bowed spring clamps 11 are pivotally secured to the outer faces of the pressing 95

leaves 4 and are adapted to have the opposite ends of the same engaged beneath the rolled flanges 6 and the oppositely disposed rolled flanges 8. Obviously, by engaging the spring clamps 11 with the flanges 6 and 8 the pressing leaves 4 will be positively and yieldably 100

maintained in engagement with the trousers arranged in the device.

Apertured bearing lugs 12 are formed integral with the sides of the body portion 1 105

at points in proximity to the opposite extremities thereof and pivotally supported in the curved slotted bearings thereof are arms 13 and 14, it being noted that the arm 14 is

of less length than the arm 13 in order that 110

the same shall conform to the taper of the body portion 1. Depressions 15 are formed in the intermediate portions of the arm 13 and serve as means for allowing the side 5 seams of the trousers to be received thereby. Finger pieces 16 may be and preferably are formed integral with the said arms 13 and 14 and, obviously, serve as means whereby the same may be swung into and out of engagement with trousers arranged in the device. Due to the peculiar form of the curved slotted bearings, it will be readily understood that the clamping arms 13 and 14 may be adjusted to different heights, thus, compensating for different sizes of the trousers. 10 Those portions of the body as arranged beneath the clamping arms 13 and 14 are serrated or scored as at 17 and serve to prevent the slipping or undue movement of the extremities of the trousers during the engagement of the clamping arms 13 and 14 therewith. It is to be noted, that by swinging the clamping arms 13 and 14 downwardly into engagement with the adjacent portions 15 of the trousers arranged in the device, the same will be securely clamped onto the body portion of the said device. Further, by swinging the clamping arms 13 and 14 outwardly, the trousers may be slightly stretched 20 to a greater extent.

To permit the securing of the device to suitable supports, such as the drawer of a wardrobe or the like, a plurality of openings generally indicated by the numeral 18 are 25 formed in the sectional body portion 1 and will permit the passage of screws or like fastening devices therethrough. A larger opening 19 is formed in the reduced portion of the body 1 and permits the device to be engaged with a hook or other support when 30 it is desired and folded into compact form.

In operation, the trousers are properly folded and placed upon the sectional body portion 1, whereupon the pressing leaves 4 are swung thereover and the spring clamps 45 11 and buttons 10 properly adjusted to cause positive engagement of the said leaves with the trousers. If desired, the trousers may be damped at points in proximity of the 50 creases therein, thus, facilitating the reshaping of the same. Previous to the engagement of the pressing leaves 4 with the trousers, the clamping arms 13 and 14 are engaged with the same, thus, stretching them 55 and insuring proper reshaping thereof without causing injury to the fabric. Should the trousers be constructed from exceedingly heavy material or more than one pair of trousers arranged in the device, the clamping arms 13 and 14 may be adjusted in the 60 curved slotted bearings of the lugs 12 accordingly.

I claim:

1. A garment pressing device including a body portion, leaves hinged to said body portion, clamping means carried by the leaves and engageable with the body portion, and arms pivotally engaged with the body portion and arranged transversely of the same. 65

2. A garment pressing device including a hingedly connected sectional body portion, leaves hinged to said body portion, clamping means carried by the leaves and engageable with the body portion, and arms pivotally engaged with the body portion and arranged transversely of the same. 75

3. A garment pressing device, including a foldable body portion, leaves hinged to said body portion, resilient clamping means carried by the leaves and engageable with the body portion, lugs formed integral with the body portion adjacent the opposite extremities thereof having curved bearing slots formed in the same, and arms pivotally engaged in said slots and disposed transversely of the body portion. 80

4. A garment pressing device, including a body portion, leaves hinged to said body portion, spring clamping means carried by the leaves and engageable with the body portion, rotatable buttons carried by said leaves and engageable with the body portion, arms pivotally engaged with the body portion at points in proximity of the opposite extremities thereof, those portions of the body adjacent the arms being serrated, as and for the purpose set forth. 90

5. A garment pressing device, including a body portion having rolled flanges formed upon the opposite marginal edges thereof, leaves hinged to said body portion, spring clamping means carried by the leaves and engageable under said rolled flanges, and arms pivotally engaged with the body portion at points in proximity of the opposite extremities thereof and arranged transversely of the same, said arms having depressions formed in the intermediate portions thereof. 100

6. A garment pressing device, including a hingedly connected sectional body, rolled flanges formed upon the opposite marginal edges of said body, leaves hinged to the body, spring clamping means carried by the leaves engageable under said rolled flanges, adjustable arms pivotally engaged with the body portion at points in proximity of the opposite extremities of the same, said arms having depressions formed in the intermediate portions thereof. 110

In testimony whereof, I affix my signature hereto.

ROBERT W. VAN BUREN.
